Fig. 2

Fig. 3

Fig. 4

Fig. 5

FIGURE 1 is an isometric view of a combined cover and guard for a foot operated electric switch unit incorporating my new design;

FIG. 2 is an elevational view of one side thereof, the opposite side being a mirror image;

FIG. 3 is a front end elevational view thereof;

FIG. 4 is a top view thereof; and

FIG. 5 is a rear end elevational view thereof.

The essential features of the design reside in the portion shown in solid lines and the broken line showing of a switch is for illustrative purposes only.

I claim:

The ornamental design for a combined cover and guard for a foot operated electric switch unit, substantially as shown and described.
